CLAIM

The ornamental design for a seat for children, for fixing on cycles or motorcycles, as shown and described.

DESCRIPTION

FIG. 1 is a front right perspective view of a seat for children for fixing on bicycles or motorcycles showing my new design.

FIG. 2 is a right side view thereof;

FIG. 3 is a left side view thereof;

FIG. 4 is a front view thereof;

FIG. 5 is a top view thereof;

FIG. 6 is a bottom view thereof; and,

FIG. 7 is a rear view thereof.
